UNITED STATES PATENT OFFICE.

JOHN BRZEZICKI, OF PITTSBURGH, PENNSYLVANIA.

SAFETY LOCK FOR TRUNKS AND THE LIKE.

1,406,822.

Specification of Letters Patent. Patented Feb. 14, 1922.

Application filed September 15, 1921. Serial No. 500,800.

To all whom it may concern:

Be it known that I, JOHN BRZEZICKI, a citizen of Poland, residing at Pittsburgh, in the county of Allegheny and State of Pennsylvania, have invented certain new and useful Improvements in Safety Locks for Trunks and the like, of which the following is a specification.

The primary object of the invention is the provision of a lock for trunks, cabinets, boxes and the like whereby the lid or cover member is securely held in closed position releasable only by means of a peculiar key in the hands of a person familiar with the manner of operating the lock, the latter being extremely difficult to manipulate by one unfamiliar with its peculiar construction.

A further object of the invention is the provision of a lock having double securing means, one adapted for release by imparting movements to secret portions of the exterior of the lock structure and the other releasable by means of certain manipulations of a particular key in connection with a secret releasing means.

A still further object of the invention is to provide a receptacle lock having a safety key hole protector and mechanism whereby a particular key must be manipulated in certain ways for both locking and releasing the mechanism, thereby preventing an unauthorized person from gaining access to the interior of the receptacle.

A still further object of the invention is to provide a receptacle lock having an exterior ornamental appearance with no visible means for operating the lock, the same however being readily released by means of a peculiar key operating one portion thereof and secret movable members adapted for operating the remaining releasable locking mechanism.

My lock is inexpensive to manufacture and possesses great strength and durability.

With these general objects in view the invention consists in the novel combination and arrangement of parts hereinafter more fully described in connection with the accompanying drawings, and in which like reference characters designate corresponding parts throughout the several views.

In the drawings,

Figure 1 is a front elevation of a portion of a receptacle such as a trunk provided

with my invention in its locked arrangement,

Figure 2 is an elevational view of the lock mechanism with the rear or inner plate removed and the hold-fast devices for mounting the lock on the receptacle being shown in horizontal section,

Figures 3, 4 and 5 are enlarged detail sectional views taken upon lines III—III, IV—IV and V—V of Figure 1,

Figures 6, 7 and 8 are enlarged detail sectional views taken upon lines VI—VI, VII—VII and VIII—VIII of Figure 1, and

Figure 9 is a perspective view of the peculiar form of key employed with my lock.

Referring more in detail to the drawings, my invention is herein illustrated in connection with a trunk 10 having a hinged lid 11, the lid being held in closed position by two hasps 12 and 13, hinged as at 14 to ornamental anchor plates 15 and 16 respectively, permanently secured to the lid 11 with the hinges 14 positioned adjacent the lower edge 17 of the lid 11.

The lock mechanism is carried by a rectangular front plate 17 having a rear plate 18 secured thereto by suitable posts 19, 20, 21 and 22 and all of which is countersunk in a chamber 23 in the outer face of the trunk wall 10. The plate 17 is secured in position upon the trunk by means of as many bolts or screws 24 as may be advisable, five thereof designated 25, being visible upon the outer face of the plate 17. To make the showing of the bolt heads uniform upon the plate 17, an additional head 26 is riveted to the plate 17 while a sliding head 27 is provided substantially centrally at the top of the plate 17 and a similar sliding head 28 at the lower corner adjacent the hasp 13.

The hasp 12 has a squared housing 29 projecting inwardly through a rectangular opening 30 in the plate 17 when the hasp 12 is closed, a normally projected spring-pressed catch 31 being at such times enlarged beneath the plate 17 securing the hasp 12 in its locking position. A spring 32 upon the inner face of the hasp 12 engages the outer face of the plate 17 for causing the hasp 12 to automatically fly outward when the catch 31 is released from its engagement with the lower side of the open-

ing 30. The hasp 12 is positioned within a U-shaped guard 33 upon the plate 17 when the hasp is closed, the latter having an upturned lower end 34 adapted for fitting within 5 in the lower closed end of the guard 33.

The catch 31 is adapted to be manually released by sliding the head or button 27 upwardly, the button 27 having a shank 35 slideable through a slot 36 in the plate 17 and 10 carried by an angular lever 37 pivoted as at 38 to the inner face of the plate 17. A spring 39 encircles the post 19 and is anchored at one end to a stud 40 carried by the plate 17 and at its other end to the lever 37 as at 41 15 for normally holding the button 27 depressed and the lower end portion 42 of the lever 37 elevated. An angular rocker 43 pivoted at 44 to the plate 17 is pivotally connected to the lower end 42 of the lever 37 by 20 a link 45 while the opposite free end 46 of the rocker 43 is normally positioned adjacent the cap 31 when the hasp 12 is in its closed position.

A latch 47 in the form of a hook is pivoted as at 48 to the plate 17 normally held overlying the lever 37 by means of a spring 49 engaging the lower end of the latch 47 and whereby the lever 37 is maintained against movement until the latch 47 is released. Suitable initials such as "J" and "B" designated 50 and 51 respectively are secured upon the outer face of the plate 17 at opposite sides of the button 27. A short arm 52 is pivoted to the latch 47 having a 35 suitable piece 53 of the plate 17 carried by the arm 52 beneath any suitable portion of the initial 51 such as the upper arcuate portion 54 thereof.

The operation of the locking mechanism 40 for the hasp 12 will be fully understood from this detailed description thereof, the closing of the hasp 12 within the guard 33 depressing the normally bent spring 32 and engaging the catch 31 beneath the plate 17 45 with the housing 29 projected inwardly through the opening 30. The end 46 of the releasing rocker 43 is normally positioned adjacent the catch 31 and upon placing any device such as a pencil through the portion 50 54 of the initial 51, the plate portion 53 may be depressed against the spring 49, thereby releasing the latch 47 from the lever 37. When the lever 37 is released in this manner, the button 27 may be manually shifted 55 upwardly thereby depressing the link 45 and upwardly moving the rocker 43 to elevate the catch 31 to its released position and whereupon the spring 32 causes the hasp 12 to fly open. Upon releasing the button 27, 60 the spring 39 returns the lever 37, link 45 and rocker 43, to their normal positions while the spring 49 returns the latch 47 to its engaging position overlying the lever 37.

The hasp 13 is similar in construction to 65 the hasp 12 having a U-shaped guard 33

and a lower upturned end 34' while a leaf spring 32' secured beneath the hasp 13 causes the latter to fly open when the loop 55 on the lower side of the hasp 13 is released when in its closed position inwardly projecting through a slot 56 in the plate 17. The loop 55 has a knob 57 adjacent the plate 17 when the hasp 13 is closed for automatic engagement by a spring-pressed lever 58 at the upper angular portion 59 thereof. The 75 false head or button 28 has its shank 60 slideable through a slot 61 in the plate 17 and carried by a link 62 pivoted at its upper end to the lever 58 in such a manner as to pivotally move the lever 58 out of engagement 80 with the notch 37 when the button 28 is forcibly lowered. The spring 63 surrounds the post 21 forming a pivot for the lever 58 with one end of the spring secured as at 64 to the lever 58 and its other end anchored to 85 a stud 65 on the inner face of the plate 17. The spring 63 normally returns the lever 58 to the upward limit of its travel with its portion 59 inwardly of the plate opening 56, whereby the closing of the hasp 13 and the 90 entry of the loop 55 through the opening 56 into the notch 37 is made for retaining the hasp 13 closed until the button 28 is again moved downwardly.

The description of the invention so far 95 pointed out deals with boltless mechanism for holding the hasps 12 and 13 against opening until some secret portions of the visible lock construction have been manually operated. These are safety features by 100 reason of the fact that a person not familiar with the construction and operation of the device would find great difficulty in releasing the hasps 12 and 13 in the manner described, and for certain purposes such mechanism is sufficient for holding the lid 11 in 105 closed position upon the trunk 10 for ready release by the owner whenever desired, without the employment of any key or specially designed implement.

When it is desired to more securely lock the hasp 13, a key 66 is provided for longitudinally moving a bolt 67 slidably mounted inwardly of the plate 17, a suitable key hole 68 being provided through the plate 17 for 115 admitting the key 66. The bolt 67 is slidably mounted between the plates 17 and 18 through a loop 69 and spaced companion lugs 70 and 70' carried by the plate 17, the opening of the loop 69 being in alignment 120 with the opening 71 in the loop 55 whereby the bolt passes through the loop 71 when projected by means of the key 68 and is retracted out of the loop 71 in its released position when withdrawn as illustrated in 125 Fig. 2. A key-hole guard is provided in the form of an ornamental elongated plate 72 having a pin 73 at its upper end journaled through the plate 17 with a coil spring 74 adapted to normally throw the guard plate 130

72 pivotally away from the key hole 68 as illustrated by dotted lines in Fig. 1. When the plate 72 is forced against the spring 74 to its upright position overlying the key 5 hole 68, a pin 75 slideable through the plate 17 and carried by a spring 76 secured at one end 77 to the inner side of the plate 17 engages within a socket 78 on the inner side of the plate 72, substantially centrally of the 10 lower end thereof for retaining the plate 72 in its covering position. The spring 76 has an outwardly projecting lug 79 at the opposite end thereof from the end 77 of the spring 76 and this lug 79 projects through 15 an opening 80 in the plate 17 for ready engagement by the beveled end 81 of the angular ward 82 of the key 66 and whereby the lug 79 is depressed and releasing the pin 75 from the cover plate 72 and permitting the 20 spring 74 to swing the plate 72 with the key hole 68 uncovered as heretofore set forth. An arcuate guard 83 overlies the lower end of the pivoted plate 72 as well as the lug 79, whereby the lug 79 is normally obscured 25 from view although in a position to permit the angular ward 82 to be positioned with its oblique end portion 81 beneath the guard 83 for depressing the lug 79 and releasing the pin 75, causing the automatic 30 opening of the key hole guard plate 72. With the bolt 67 retracted as shown in Fig. 2, the key 66 is positioned through the key hole 68 and the ward 82 engaged against the forward side 84 of the notch 85 in said bolt 35 67 for projecting the bolt through the loop 55 on turning the key 66 one revolution. A further revolution of the key 66 engages the ward 82 against the forward side 86 of a relatively longer notch 87 in the bolt 67 for 40 further projecting the bolt to its full locking position. A releasing spring lever 88 is anchored at one end at 89 to the bolt 67 and is brought upon fully projecting the bolt with its substantially central thickened 45 portion 90 in such relation to the hole 68 as to engage the key ward 82 with the portion 90 upon a short revolution of the key 66 and whereby the spring lever 88 is forced upwardly permitting a beveled lug 91 to 50 engage within a socket 92 in the thickened portion 90 and thereby hold the releasing lever 88 out of the path of movement of the key ward 82 for preventing the key from returning the bolt 67 to its unlocked position. 55

When it is desired to retract the bolt 67 it is necessary to inwardly move the lug 91 and this lug being carried by a spring 93 which is pivoted to the plate 18 at 94 may 60 be so moved away from the plate 17 by forcibly depressing inwardly the key post 95 which is carried by the said spring 93 and freely moves through an opening 96 in the plate 18. The releasing operation is therefore 65 accomplished by first depressing the

key post 95 with any convenient member such as the key 66 and then inserting the key with its axial bore 97 upon the post 95 and turning the same to engage the ward 82 with the forward side 98 of the portion 90 70 of the spring lever 88 whereby the bolt 67 is retracted one step and a further turning of the key 66 brings the ward 82 into engagement with the rear face 99 of the notch 85 giving the final retraction to the bolt 67 and 75 placing the same in its unlocked position.

A detent 100 is pivoted at 101 to the plate 17 with an elongated lower portion 102 normally positioned in line with the open sides of the slots 85 and 87 and with an intermediate shoulder 103 of the detent 100 positioned within a top notch 104 of the bolt 67 when the bolt is retracted. Upon every turn of the key 66, its ward 82 engages the portion 102 of the detent 100 and raises the 85 shoulder 103 above the upper edge of the bolt 67 for automatically releasing the bolt from the shoulder 103 whenever the key 66 is turned for actuating the bolt in either direction. The shoulder 103 seats within an 90 intermediate notch 105 in the top of the bolt 67 when the bolt is projected one step and into the rear notch 106 in the top of the bolt 67 when the bolt is entirely projected in its locked position. After the bolt is fully projected and the releasing spring lever 88 is caught by the lug 91 so as to be out of the path of movement of the key ward 82 which prevents the retraction of the bolt 67, the 95 detent portion 102 is still within the path of 100 movement of the ward 82 giving the impression to an unauthorized person endeavoring to pick the lock that the bolt actuating mechanism is being operated.

The complete operation of the lock mechanism will be fully understood from this detailed description thereof, the bolt 67 being releasable upon depressing the key post 95 to cause the releasing lever 88 to spring downwardly into position and whereupon 110 two revolutions of the key 66 fully retract the bolt. The bolt is then fully projected by two reverse turns of the key 66 and the releasing lever 88 is elevated for holding by the lug 91 upon a short turn given to the 115 key 66.

When the bolt 67 is locked, the key hole guard 72 is returned to its normal vertical position, automatically engaging the pin 75 with the lower socket of said guard 72 120 whereby the completely secured lock presents the appearance shown in Fig. 1 of the drawings.

A return spring 107 has its free end mounted upon the retaining member 100 125 for returning the shoulder 103 to its adjacent notch of the bolt 67, the spring 107 being coiled about and anchored to a post 108 beneath the plate 17.

While the form of the invention herein 130

shown and described is what is believed to be the preferred embodiment thereof, it is nevertheless to be understood that various forms, modifications and arrangements of the parts may be made without departing from the spirit and scope of the invention as claimed.

What I claim as new is:

1. A lock comprising a mechanism plate having a slot, a hinged hasp, a spring pressed catch carried by the hasp adapted for projecting inwardly through the slot in engagement with the plate when the hasp is closed, articulated releasing means for the catch inwardly of the plate and sliding actuating means for the articulated means outwardly of the plate.
2. A lock comprising a mechanism plate having a slot, a hinged hasp, a spring pressed catch carried by the hasp adapted for projecting inwardly through the slot in engagement with the plate when the hasp is closed, articulated releasing means for the catch inwardly of the plate, slidable actuating means for the articulated means outwardly of the plate, a securing latch for the articulated means when in its inoperative position and a partially obscured separated portion of the plate operatively connected to the latch adapted for releasing the latch and rendering the articulated means operable.
3. A lock of the class described comprising a mechanism mounting plate having a slot, a swinging hasp adapted for substantially flat engagement with the plate when in locked position, a housing upon the hasp positioned through the slot when locked, a normally projected spring pressed catch provided for the housing adapted for automatic engagement inwardly of the plate upon closing the hasp and articulated releasing means for the catch operable outwardly of the plate.
4. A lock of the class described comprising a mechanism mounting plate having a slot, a swinging hasp adapted for substantially flat engagement with the plate when in locked position, a housing upon the hasp positioned through the slot when locked, a normally projected spring pressed catch provided for the housing adapted for automatic engagement inwardly of the plate upon closing the hasp, articulated releasing means for the catch, a slidable button outwardly of the plate operatively connected to said articulated means and a retaining latch for the articulated means inwardly of the plate adapted for release outwardly of the plate.
5. A lock of the class described comprising a mechanism mounting plate having a slot, a swinging hasp adapted for substantially flat engagement with the plate when in locked position, a housing upon the hasp

positioned through the slot when locked, a normally projected spring pressed catch provided for the housing adapted for automatic engagement inwardly of the plate upon closing the hasp, articulated releasing means for the catch, a slidable button outwardly of the plate operatively connected to said articulated means, a retaining latch for the articulated means inwardly of the plate, an operating lever for the latch, a severed portion of the plate mounted upon said lever in normal alignment with the surrounding portion of the plate and a partial obscuring means overlying the edge of the severed plate portion outwardly.

6. A lock of the type described comprising a plate having a slot, a hinged hasp co-operating therewith, a loop upon said hasp positioned through the slot when the hasp is closed in substantially flat engagement with the plate, the loop having a notch inwardly of the plate when the hasp is closed, an angular lever pivoted inwardly of the plate having its angular portion provided with a path of travel inwardly of the notch when the hasp is closed, a normal positioning spring for the lever whereby the angular portion of the lever is adapted for automatic return inwardly of the slot subsequent to the retraction of the lever and a button slidably mounted outwardly of the plate operatively connected to the lever inwardly of the plate.

7. A lock comprising a hasp and a plate, locking mechanism for the hasp carried by the plate, the plate having a key-receiving slot, an elongated guard pivoted outwardly of the plate adapted for covering and uncovering the key hole upon pivotal movement, an arcuate cover member upon the plate overlying the free end of the guard at all times, releasable retaining means for the guard when overlying the slot operable beneath the cover member and swinging means for the guard when the guard is released.

8. A lock comprising a hasp and a plate, locking mechanism for the hasp carried by the plate, the plate having a key-receiving slot, an elongated guard pivoted outwardly of the plate adapted for covering and uncovering the key hole upon pivotal movement, an arcuate cover member upon the plate overlying the free end of the guard at all times, an operating spring for the guard inwardly of the plate adapted for swinging the guard away from the slot and adjacent one end of the cover member, a spring pressed pin beneath the plate adapted for holding engagement with the guard when in its closed position overlying the slot and releasing means for the pin projecting through the plate in a partially obscured position beneath the cover member at a point adjacent the guard when the latter is closed over the slot.

9. A lock comprising a plate, a sliding bolt carried by the plate, an operating key for the bolt, a releasing spring lever upon the bolt, the bolt being adapted for projection by the key and releasable engaging means for the lever adapted for retaining the lever inoperative upon a subsequent turning of the key after the bolt is fully projected.
10. A lock comprising a plate, a sliding bolt carried by the plate, an operating key for the bolt, a releasing spring lever upon the bolt, the bolt being adapted for projection by the key, releasable engaging means for the lever adapted for retaining the lever inoperative upon a subsequent turning of the key after the bolt is fully projected, a post for the key normally projecting inwardly of the slot and operative connections between said post and the lever engaging means whereby such means is released upon inward movement of the post rendering the lever operable during the bolt-releasing operation.
11. A lock comprising a plate, a sliding bolt carried by the plate, an operating key for the bolt, a releasing spring lever upon the bolt, the bolt being adapted for projection by the key, releasable engaging means for the lever adapted for retaining the lever inoperative upon a subsequent turning of the key after the bolt is fully projected, a post for the key normally projecting inwardly of the slot, operative connections between said post and the lever engaging means whereby such means is released upon inward movement of the post rendering the lever operable during the bolt-releasing operation, releasable means pivoted adjacent the bolt adapted for retaining the bolt in its projected or retracted position with a portion thereof positioned in the releasing path of movement of the key when turned during operation in either direction and a return spring for said retaining means.
12. A lock comprising a plate having a slot, a hasp, a loop upon the hasp adapted for positioning through the slot, an automatic engaging lever for the loop releasable outwardly of the plate adapted for the initial locking of the hasp when closed upon the plate, a slidable lock bolt beneath the plate adapted for movement through said lock when the bolt is projected and means for projecting and retracting the bolt at will.
13. A lock comprising a plate having a slot, a hasp, a loop upon the hasp adapted for positioning through the slot, an automatic engaging lever for the loop releasable outwardly of the plate adapted for the initial locking of the hasp when closed upon the plate, a slidable lock bolt beneath the plate adapted for movement through said lock when the bolt is projected, means for projecting and retracting the bolt at will, an operating key for the bolt, a spring-releasing lever for the bolt mounted on the bolt within the path of movement of the key when turning in the bolt-projecting direction after the bolt is locked and engaging means for the lever when in its inoperative position.
14. A lock comprising a plate having a slot, a hasp, a loop upon the hasp adapted for positioning through the slot, an automatic engaging lever for the loop releasable outwardly of the plate adapted for the initial locking of the hasp when closed upon the plate, a slidable lock bolt beneath the plate adapted for movement through said lock when the bolt is projected, means for projecting and retracting the bolt at will, an operating key for the bolt, a spring-releasing lever for the bolt mounted on the bolt within the path of movement of the key when turning in the bolt-projecting direction after the bolt is locked, engaging means for the lever when in its inoperative position, a combined post for the key and releasing means for the lever, the plate having a key hole slot with said combined means projecting therein and a normally closed releasable guard pivotally mounted overlying the slot outwardly of the plate.

In testimony whereof I affix my signature.

JOHN BRZEZICKI.
